GRINDING WHEEL TRUING APPARATUS

Carl G. Flygare and Herbert A. Silven, Worcester,
Mass., assignors to Norton Company, Worcester,
Mass., a corporation of Massachusetts

Application October 8, 1935, Serial No. 44,069

15 Claims. (Cl. 125—11)

This invention relates to grinding machines, and more particularly to a grinding wheel truing apparatus which is adapted to true a plurality of grinding wheels to a predetermined irregular contour.

One object of this invention is to provide a simple, thoroughly practicable grinding wheel truing apparatus for truing the periphery of a grinding wheel to an exact contour for grinding work of non-cylindrical shape.

Another object of this invention is to provide a grinding wheel truing apparatus for simultaneously truing the peripheries of a plurality of grinding wheels to predetermined irregular contours.

Another object of this invention is to provide a grinding wheel truing apparatus for truing the periphery of a large grinding wheel to an irregular contour, in which the rotative speed of the grinding wheel is automatically slowed down to a proper speed for truing.

Another object of this invention is to provide a hydraulically operated cam control truing apparatus for truing the peripheries of a plurality of wheels to predetermined irregular contours.

Another object of this invention is to provide a grinding wheel truing apparatus for truing a plurality of wheels, in which a control mechanism is provided to automatically move and hold a plurality of truing tools in an inoperative position during the grinding period.

A further object of this invention is to provide an electrically controlled, hydraulically operated feeding mechanism for feeding a truing apparatus to move the diamond or truing tool toward the peripheries of the grinding wheel or wheels by a small adjustable increment.

Other objects will be in part obvious or in part pointed out hereinafter.

The invention accordingly consists in the features of construction, combinations of elements, and arrangements of parts as will be exemplified in the structure to be hereinafter described, and the scope of the application of which will be indicated in the following claims.

In the accompanying drawings in which is shown one of various possible embodiments of the mechanical features of this invention,

Fig. 1 is a fragmentary plan view of a grinding machine having parts broken away and shown in section to more clearly show the construction of the wheel truing apparatus;

Fig. 2 is a fragmentary plan view of the wheels and the truing apparatus combined with a piping and electrical diagram to show the operation of

the hydraulic control and electrical control apparatus;

Fig. 3 is a cross-sectional view, on an enlarged scale, through the truing apparatus, taken approximately on the line 3—3 of Fig. 1; 5

Fig. 4 is a fragmentary horizontal section, on a reduced scale, taken approximately on the line 4—4 of Fig. 3;

Fig. 5 is a fragmentary rear view, partly in section, of the truing tool cross feeding mechanism; 10

Fig. 6 is an end elevation, on an enlarged scale, of the vane motor for moving the truing tools to inoperative positions, showing the control valve for the motor in section; 15

Fig. 7 is a fragmentary detail view, on an enlarged scale, of the mountings of the valve control levers, taken approximately on the line 7—7 of Fig. 1;

Fig. 8 is a fragmentary view, on an enlarged scale, of the timing adjustment between the drive shaft and the camshaft for controlling the movement of the truing tool; 20

Fig. 9 is a left end elevation, on an enlarged scale, of the timing connection shown in Fig. 8; 25

Fig. 10 is a cross sectional view of the fluid pressure control and actuating mechanism for the truing apparatus, taken approximately on the line 10—10 of Fig. 1. 30

The embodiment of the invention selected for illustration comprises a grinding machine having a base 10 which supports a rotatable grinding wheel spindle 11 in bearings 12. The grinding wheel spindle 11 carries a wheel mounting 13 which in turn supports a plurality of grinding wheels 14, 15, 16 and 17. The base 10 also supports a rotatable work support comprising a headstock 20 and a footstock (not shown) which are arranged to rotatably support a work piece, such as a camshaft 21, having a plurality of cams 22, 23, 24 and 25 which are arranged to be simultaneously ground by the grinding wheels 14, 15, 16 and 17. The work support including the headstock 20 and the footstock is preferably supported on a transversely movable carriage 26 which is supported on slideways 18 and 19 and is arranged to be moved transversely toward and from the grinding wheel peripheries by a suitable feeding mechanism (not shown) to grind the work pieces to a predetermined size and contour. The mounting for the work supports and the feeding mechanism therefor have not been illustrated in the present application since they are not considered part of the present invention. 45

50

55

The feeding mechanism for the work support is fully disclosed and described in the prior patent to Wood No. 1,969,997 dated August 14, 1934, to which reference may be had for a detailed disclosure of this mechanism.

The wheel spindle 11 is rotated by means of an electric motor 28 having a driving pulley 29 and transmitting power to a belt 30 to a pulley 31 on the end of the wheel spindle 11.

- 10 The grinding wheels are trued to an irregular non-circular contour which is the conjugate of the desired work contour, such as a cam. The grinding wheels and the work piece 21 are rotated in synchronism so that the irregular shape of the 15 peripheries of the grinding wheels will serve to generate a conjugate shape on the cams 22, 23, 24 and 25. A bevel gear 34 is mounted on the end of the wheel spindle 11 and meshes with a bevel gear 35 mounted on a transverse sleeve 36. The 20 sleeve 36 is connected by a shaft 37 with a rotatable sleeve 38 in a gear box 39 carried by the work carriage. The sleeve 38 carries a bevel gear 40 which meshes with a bevel gear 41. The bevel gear 41 is connected by a shaft 42 to rotate the 25 headstock spindle and thereby rotate the work piece, such as the camshaft 21, in synchronism with the rotation of the grinding wheels.

In order that the grinding wheels may be properly trued to a predetermined non-circular contour which is the conjugate of the shape desired to be produced on the finished work piece, it is desirable to provide a truing apparatus for generating the predetermined shape on the peripheries of the wheels. This is preferably accomplished 35 by providing a truing apparatus 45 with a plurality of truing tool slides 46, 47, 48 and 49, each of which carries a diamond or truing tool 50, 51, 52 and 53 respectively which are arranged to simultaneously true the peripheries of the wheels 40 14, 15, 16 and 17. The slides are each supported on a pair of opposed slideways 54 and 55 (Fig. 3), only one set of ways 54 and 55 being shown in detail. The truing tool slides 46, 47, 48 and 49 are arranged to move in a path normal to the 45 axis of the grinding wheel and are arranged for a transverse movement toward and from the wheel axis to generate a predetermined shape on the periphery of the wheels, which shapes are the conjugate of the shape to be produced on the 50 cams 22, 23, 24 and 25.

In order that the truing tool slides 46, 47, 48 and 49 may be moved transversely to true the wheel to a predetermined contour, a rotatable master camshaft 60 is supported in bearings 61, 55 62 and 63 in the truing apparatus frame 45. The camshaft 60 carries a plurality of master cams 64, 65, 66 and 67 which are arranged to move the truing tool slides 46, 47, 48 and 49 respectively. Each of the truing tool slides 46, 47, 48 and 49 are 60 provided with an adjustable follower 68, only one of which has been illustrated in detail in Figs. 3 and 4. The truing tool slides are held in an operating position with the follower 68 in engagement with the cams 64, 65, 66 and 67 by means of a pair of springs 69 and 70 which are interposed between the slides and the ends of the truing apparatus casing 45.

In order that the master camshaft 60 and the cams mounted thereon may be rotated in synchronism with the rotation of the grinding wheel, the shaft 60 is connected to a shaft 71 carrying a bevel gear 72 which meshes with a bevel gear 73 mounted on a transverse sleeve 74 which is connected by a shaft 75 with the sleeve 36 so that the 75 rotative power of the wheel spindle is directly

connected to rotate the camshaft 60 in synchronism therewith.

Each of the cam followers 68 are adjustably supported on their respective slides by means of an adjusting screw 77 which is screw threaded 5 into the slide and has its end abutting against the end of the cam follower 68. A lock nut 78 is threaded onto each of the screws 77 and has a tubular extension 79 which passes through an aperture 80 in the truing apparatus casing and 10 has its end bearing against the end of the truing tool slide. By manipulation of the screw 77 and the lock nut 78, the position of the follower may be adjusted so as to vary the operative position of the truing tool relative to the camshaft 60. 15

In order that the entire truing apparatus assembly 45 may be adjusted bodily toward and from the grinding wheel assembly, a transversely movable slide 82 is mounted on slideways 83 and 84 and is arranged to be moved transversely 20 thereon by means of a cross feed screw 85 which is rotatably supported in a bracket 86 on the base 10 and meshes with a nut 87 carried by the slide 82. The slide 82 carries the truing apparatus 45 and also the gear box 88. The driving shaft 75 25 telescopes within the sleeve 74 so as to permit the gear box 88 to move transversely when the diamond truing tools are fed toward and from the wheel periphery.

The feed screw 85 may be rotated manually by 30 means of a graduated hand wheel 90 to manually position the truing tools relative to the grinding wheel. In the preferred construction, however, an electrically controlled, hydraulically operated mechanism is provided so that the screw 85 may 35 be turned by very small increments by means of an electrical push button 91 mounted on the front of the machine base. When the push button 91 is closed, power from a source of power labeled "Power line" serves to energize a solenoid 92 to 40 shift a valve piston 93 in the valve 94 into the position illustrated in Fig. 5. Fluid under pressure is pumped from a reservoir 95 in the base of the machine through a pipe 96 by means of a gear pump 97 and forced through a pipe 98 and 45 a pipe 99 into a valve chamber 100. The fluid under pressure passes out of chamber 100 through a V-port 101 into a cylinder chamber 102 to cause a piston 103 to move upwardly within the cylinder 104 against the tension of a spring 105. A 50 piston rod 106 connected to the piston 103 is connected by a stud 107 at the end of a long arm 108 of a bell crank lever 109. The short arm of the bell crank lever 109 is formed as a gear segment 110 which meshes with gear teeth 111 which are 55 on a portion of a plate 112 which is rotatably supported on the outer end of the feed screw 85. The plate 112 carries a pair of pivotally mounted pawls 113 which are arranged to engage the teeth of a ratchet wheel 114 which is fixedly connected 60 to rotate the feed screw 85. A spring 115 connected between a stud 116 on the bracket 86 and a stud 117 on the plate 112 tends to normally turn the ratchet pawls 113 in a clockwise direction. The clockwise movement of the pawls 113 65 is limited by an adjustable stop screw 118 mounted in a boss 119 which projects from the bracket 86. A similar adjustable stop screw 120 carried by a projecting boss 121 serves to limit the counter-clockwise movement of the pawl carrying plate 70 112. When the push button 91 closes the circuit and shifts the valve piston 93 into the position illustrated in Fig. 5, fluid under pressure passing into the chamber 102 moves the piston 103 upwardly into the position illustrated in Fig. 5, caus- 75

ing the bell crank lever 109 to rock in a clockwise direction. This movement in turn rocks the plate 112 through gear segment 110 and a gear segment 111 in a counterclockwise direction so that 5 the pawls 113 engaging the ratchet wheel 114 cause a partial rotation of the feed screw 85 to feed the truing apparatus 45 toward the peripheries of the grinding wheels. By adjusting the 10 position of the screws 118 and 120, the mechanism may be adjusted to pick up one or more teeth of the ratchet wheel at each actuation of the mechanism.

When the push button 91 is released, the 15 solenoid 92 is deenergized and the released tension of a spring 122 moves the piston 93 toward the right, as viewed in Figs. 2 and 5, into the position illustrated in Fig. 2. In this position of the piston 93, fluid within the chamber 102 may exhaust through a V-port 123 through the valve chamber 20 100 and exhaust through a pipe 124 into the reservoir 95.

In order that the truing tools 50, 51, 52 and 53 may be traversed across the face of the grinding wheel to true the same, the transverse slide 82 25 is provided with a longitudinally extending slideway 125 which mates with a corresponding way 126 on the under side of the truing apparatus 45 and serves to guide the entire truing apparatus longitudinally of the slide 82 to carry the diamonds 30 across the face of the grinding wheel. The truing apparatus 45 is traversed longitudinally on the slideway 125 by means of a hydraulically actuated mechanism including a cylinder 127 which slidably supports a piston 128 35 which is connected by a piston rod 129 and a stud 130 with a link 131. The link 131 is connected by means of a stud 132 with a rock arm 133 pivotally mounted on a stud 134 on the under side of the truing apparatus 45. The rock arm 133 is 40 provided at its front end with a yoked projection 135 which slidably supports a bushing 136. The bushing 136 is provided with a central aperture 137 and is connected by a stud 138 depending from the truing apparatus 45. When the piston 128 is moved in either direction, the linear motion of the piston will be transmitted through link 131 to rock the arm 133 and through the stud 138 cause a longitudinal traversing movement of the 45 truing tools relative to the grinding wheels. The length of the traversing stroke of the truing tools may be adjusted by means of a pair of adjustable stop screws 140 and 141 which are 50 mounted in collars 142 and 143 on opposite ends of the piston rod 129. The adjustable screws 140 and 141 are arranged to engage the ends of the cylinder head and to limit the extent of movement 55 of the piston 128. By manipulating the screws 140 and 141, the movement of the piston 128 in either direction may be adjusted so that the truing tools move across the face of the grinding 60 wheels to the desired extent.

Fluid under pressure is admitted to actuate the piston 128 to traverse the truing apparatus 45 through pipe 98 and pipe 144 to a reversing valve 65 145. The reversing valve 145 is of the sliding piston type valve including a valve stem 146 and a plurality of valve pistons 147, 148, 149 and 150. In the position of the parts as illustrated in Fig. 2, fluid under pressure enters a valve chamber 70 between pistons 148 and 149 and then passes through a passage 151 into a cylinder chamber 152 to cause the piston 128 to move to its extreme left-hand position, as illustrated in Fig. 2.

During the movement of the piston 128 toward 75 the left, as above described, fluid is exhausted

from a cylinder chamber 153 through a passage 154 and a valve chamber between valve pistons 147 and 148 and out through a pipe 155 and exhausts through a speed control valve 156 and then through a pipe 157 to exhaust into the reservoir 5 95. The valve 156 is preferably a needle valve which permits a fine adjustment of the oil exhausting from the system so that by controlling the opening of the needle valve, the speed of movement of the piston 128 and also the truing 10 apparatus is readily controlled to pass the diamond at a predetermined slow rate across the peripheries of the grinding wheels. When the reversing valve 145 is moved into its reverse position from that shown in Fig. 2, fluid under pressure passing through the pipe passes through the valve chamber between pistons 148 and 149 15 through a passage 154 into a cylinder chamber 153 to cause the piston 128 to move toward the right, which serves through the link 131 to rock 20 the arm 133 in a clockwise direction which serves to move the truing apparatus 45 toward the left, as viewed in Fig. 2, so as to traverse the diamonds from their full line position into their dotted line 25 position across the peripheries of the grinding 30 wheels. During this traversing movement, the master camshaft 60 is continuously rotated so that the diamonds are moved transversely during the traversing movement in synchronized relation with the rotation of the grinding wheel to generate a predetermined contour on the periphery of the wheel which is the conjugate of the shape desired to be produced on the periphery of the work piece.

A control knob 160 is mounted on the end of a 35 rod 161 slidably and rotatably supported in brackets 162 and 163. An arm 164 is rotatably supported on the rod 161 between collars 165 and 166. The other end of the arm 164 is connected by a stud 167 with a groove 168 in the enlarged 40 end of the valve stem 146. When the control knob 160 is moved toward the left, as viewed in Fig. 2, into the dotted line position 160, this movement serves through the arm 164 to cause a corresponding movement to the valve stem 146 to 45 reverse the flow of fluid to the cylinder 127.

It is desirable to provide a mechanism for automatically and simultaneously moving all of the truing tool slides to an inoperative rearward position after the truing operation is completed 50 so that the followers 68 are out of engagement with the cams 64, 65, 66 and 67 and the diamonds 50, 51, 52 and 53 are out of operative contact with the peripheries of the grinding 55 wheels. This is preferably accomplished by providing a transverse eccentric shaft 170 which is journaled in bearings 171, 172 and 173. The shaft 170 is rotated 180° about the axis of the bearings 171, 172 and 173. When the eccentric shaft 170 is rotated into the position illustrated in Fig. 3, the shaft 170 is out of engagement with all of the truing tool slides 46, 47, 48 and 49. In this position of the parts, as illustrated in Fig. 3, the truing tool slides are moved forward into an operating position by the tension of the springs 69 60 and 70 so that the cam followers 68 are in operative engagement with the cams 64, 65, 66 and 67.

When it is desired to move the truing tools to an inoperative position after the grinding wheels have been trued, the shaft 170 is rotated through a half turn into position 170a, as shown in dotted lines in Fig. 3. As the shaft 170 moves into this position, it engages a surface 175 on each of the truing tool slides and moves each of the slides 70 rearwardly so that the surface 175 moves into 75

broken line position 178a, as indicated in Fig. 3. By utilizing this mechanism, it is not necessary to readjust or turn the feed wheel 90 after truing. It is merely necessary to rotate the eccentric shaft 170 and move all of the truing tools 50, 51, 52 and 53 to a rearward or inoperative position. The grinding operation may then be resumed. After the grinding wheels become worn away due to grinding and need to be retrued, the shaft 170 10 may then be rocked from position 170a (Fig. 3) into 170 so as to again bring the truing tools into their operating position to dress or true the peripheries of the grinding wheels.

The partial rotation of the eccentric shaft 170 15 is hydraulically controlled by a rotary motor 177 of the single vane type having a movable vane 178 which is supported on a shaft 179 and is arranged to be moved through a half turn to shift the vane from position 178a into position 178b. 20 A reversing valve 180 serves to control the admission of fluid to the motor 177. Fluid under pressure is admitted from the pipe 98 through a pipe 181 into the valve 180. The valve 180 is of a sliding piston type having a valve stem 182 25 and valve pistons 183, 184, 185 and 186. In the position of the parts illustrated in Fig. 6, fluid under pressure is admitted from the pipe 181 through a valve port 187 into a valve chamber 188 between the valve pistons 184 and 185. Fluid 30 under pressure from the chamber 188 passes out through a port 189 into a chamber 190 within the vane motor 177 and passes through a port 191 into a chamber 192 to cause the vane 178 to rotate from position 178a into position 178b. During 35 this movement of the vane 178, fluid is exhausted from the motor chamber 192 through a passage 193 in the vane 197 into an arcuate groove 194 in the hub of the motor casing. Fluid from the arcuate slot 194 passes through a needle 40 valve 195 and a passage 196 into a chamber 197 formed in the hub of the motor casing and out through a passage 198 into a valve chamber 199 between the valve pistons 185 and 186 into an exhaust pipe 200 which returns the fluid to the reservoir 95. By utilizing the needle valve 195, 45 a regulated movement of the vane 178 may be obtained so that the truing tool slides 46, 47, 48 and 49 may be moved forward into an operating position by rotation of the eccentric shaft 170 with 50 a controlled movement so that shocks and vibrations will be eliminated when the cam followers 68 are moved into successive engagement with the cams 64, 65, 66 and 67.

When it is desired to move the truing tools to 55 an inoperative position after truing, the valve stem 182 is moved toward the right, as viewed in Fig. 6, to position the valve pistons in positions 183a, 184a, 185a and 186a. In this position of the parts, fluid is admitted through pipe 181 into the 60 valve chamber 188 between pistons 184a and 185a and through a passage 201 into motor chamber 202 and through a ball check valve 203 into a motor chamber 192 to cause the vane 178 to move from position 178b into position 178a.

In order to control the movement of the valve 65 180, the valve stem 182 is provided with a grooved spool 205 which is connected by means of pins 206 with a rock arm 207 which is mounted on the rod 161 so that the valve 180 may also be controlled by the knob 160. The rock arm 207 is 70 slidably keyed to the rod 161 by means of a pivot point set screw 208 and check nut. The pivot point slides in a keyway 209 in the shaft 161.

When the knob 160 is rotated to turn the shaft 161, the rotary motion is transmitted through

the set screw 208, keyway 209 to rock the arm 207 which serves through the pins 206 and spool 205 to move the valve stem 182 endwise to shift the position of the reversing valve 180. The rod 161 is free to move endwise due to the keyway 5 209 so as to permit the arm 164 to operate the reversing valve 145 to control the traversing movement of the truing apparatus relative to the grinding wheels. By manipulation of the single control knob 160, the vane motor 177 may be 10 operated to move the diamonds into an operating position and then the knob 160 moved in an axial direction to shift the reversing valve 145 so as to cause the diamond truing tools to traverse across the peripheries of the grinding wheels. 15

In order that the camshaft 60 may be timed to rotate in the proper relation with the rotation of the wheel spindle 11, a timing mechanism is interposed between the driving shaft 71 and the camshaft 60. This mechanism comprises a 20 flanged plate 210 which is keyed to the camshaft 60 by a key 211. The flange 210 is provided with arcuate slots 212 and 213. Bolts 214 and 215 pass through the arcuate slots 212 and 213 and are held in a plate 216 placed on a shoulder 25 on flange 210. The end of the camshaft 71 is provided with a flange 217 keyed to shaft 71 similar to flange 210 which is connected by a pin 218 with the plate 216. By adjusting the flange 210 relative to the plate 216, so that the bolts 30 214 and 215 move within the arcuate slots 212 and 213, the timing of the camshaft 60 may be regulated as desired relative to the driving shaft 71. In order to facilitate the timing adjustment of the camshaft 60, a graduated scale 219 is provided on the periphery of the flange 210 and a zero index 220 is provided on the plate 216, so that the timing of the shaft 60 may be readily adjusted by turning the plate 210 the desired 35 number of degrees on the graduated scale relative to the driving shaft 71. 40

Due to the fact that the diamonds or truing tools have a combined traversing as well as an in-and-out motion to generate a formed surface on the periphery of the wheel, it is desirable 45 to slow down the rotation of the grinding wheel for the truing operation. The slowing down of the grinding wheel is preferably accomplished automatically in timed relation with the movements of the truing tools so that when the truing tools are moved into an operative position for truing, the grinding wheel will be automatically slowed down to a desired and predetermined truing speed. This is preferably accomplished by means of a limit switch 225 which is connected 50 by means of a link chain 226 with a pulley 227 mounted on the small diameter extension of the bearing 173 of the eccentric shaft 170. When the eccentric shaft 170 is rotated to move the diamond truing tools into an operating position, the rotation of the pulley 227 releases the tension 55 on the chain 226 and closes the limit switch 225 which serves to energize the electromagnet 228 of a relay 229. The energizing of electromagnet 228 serves to move the relay arm 230 into the full 60 line position indicated in Fig. 2. This movement serves to close a circuit to cut in a variable resistance 231 which is connected with the motor 28 to slow down the rotation of the motor and therefore 65 slow down the rotation of the grinding wheels 70 14, 15, 16 and 17 to a desired peripheral speed. By adjustment of the variable resistance unit 231, the truing speed of the wheels may be varied as desired.

After the grinding wheels have been trued and 75

the shaft 170 is rocked to move the truing tools to their inoperative positions, the rotation of the pulley 227 serves to pull the chain 226 and thereby open the limit switch which deenergizes the electromagnet 228 of the relay 229, releasing the relay arm 230 so that it returns to its normal position 230a so that the full power from the power lines is connected to rotate the motor 28 and the grinding wheels at the normal grinding speed.

In the operation of this mechanism to true the grinding wheels 14, 15, 16 and 17 to the proper contour which is the conjugate of the finished work piece, the knob 160 is first rotated to shift the position of the valve 180 to admit fluid to the vane motor 177 so as to rock the eccentric shaft 170 to release the tension of the springs 69 and 70 to move all of the truing tool slides and followers 68 into operative contact with the cams 64, 65, 66 and 67 to position the diamonds 50, 51, 52, 53 and 54 in operative truing position relative to the peripheries of the grinding wheels. The knob 160 is then moved endwise to shift the valve 145 to admit fluid to cylinder chamber 153 and thereby through link 131 and rock arm 133 traverse the truing apparatus 45 to pass the truing tools across the peripheries of the grinding wheels. When the knob 160 is turned to cause the eccentric shaft 170 to rotate and allow the truing tools to move into an operating position, this motion serves to operate the limit switch 225 which through relay 229 cuts in the variable resistance 231 to slow down the speed of the motor 28 and the grinding wheel spindle 11 to a proper predetermined truing speed. The push button 91 may then be operated to cause the pawl and ratchet to feed the truing tools toward the peripheries of the grinding wheels by any desired number of increments. The truing tools may be passed across the peripheries of the wheels the desired number of times by manually shifting the control knob 160 between the position 160 and 160a, as indicated in Fig. 2. After the wheels have been trued to the desired extent, the knob 160 is rotated to shift the valve 180 into its reverse position so as to rock the eccentric shaft 170 to withdraw all of the truing tools to an inoperative position. This rocking of the eccentric shaft serves to operate the limit switch 225 to break the circuit, deenergizing the electromagnet 228 of relay 229, thereby releasing the relay arm 230 which returns into position 230a so that the full power from the power lines is conveyed to the motor 28 to rotate the motor and the wheel spindle 11 at the normal grinding speed.

It will thus be seen that there has been provided by this invention apparatus in which the various objects hereinabove set forth together with many thoroughly practical advantages are successfully achieved.

As many possible embodiments may be made of the above invention and as many changes might be made in the embodiment above set forth, it is to be understood that all the matter hereinbefore set forth, or shown in the accompanying drawings, is to be interpreted as illustrative and not in a limiting sense.

We claim:—

1. A truing apparatus for a grinding machine comprising a rotatable grinding wheel, means to rotate said wheel, a truing tool arranged to true the operative face of said wheel, means to traverse the truing tool and grinding wheel longitudinally relative to each other to true the operative face thereof, positioning means to move the tru-

ing tool to and from an operative position, means to feed the truing tool toward the operative face of the wheel to true the same to the desired extent, and a speed control mechanism which is operated by said positioning movement of the truing tool to change the speed of the grinding wheel from a grinding speed to a predetermined truing speed at the start of the truing operation.

2. A truing apparatus for a grinding machine comprising a rotatable grinding wheel, means including an electric motor to rotate said wheel, a truing tool arranged to true the operative face of said grinding wheel, means to traverse the truing tool longitudinally relative to the grinding wheel to true the operative face thereof, means to move said truing tool to and from an operating position, and a control mechanism operated in timed relation with said latter means to change the speed of said motor so as to rotate the grinding wheel at a predetermined truing speed.

3. A truing apparatus for a grinding machine comprising a rotatable grinding wheel, means including a multi-speed motor to rotate the wheel, a truing tool arranged to true the operative face of the grinding wheel, means to traverse the truing tool longitudinally relative to the grinding wheel to true the operative face thereof, means to vary the traversing speed of said truing tool, means to move said truing tool to and from an operating position, means to feed the truing tool toward the operative face of the grinding wheel to true the same to the desired extent, and means including a speed control mechanism operated in timed relation with the truing tool positioning movement to automatically slow down the speed of said motor so as to rotate the grinding wheel at a predetermined truing speed.

4. A truing apparatus for grinding machines comprising a rotatable grinding wheel, means to rotate said wheel, a truing tool which is arranged to be moved longitudinally and transversely relative to the operative face of the grinding wheel to true the same, means to traverse the truing tool longitudinally relative to the grinding wheel, means to move said truing tool transversely toward or from the operative face of said wheel to position the truing tool relative to the grinding wheel, and a control mechanism operated automatically by said transverse positioning movement to automatically change the speed of said wheel to a predetermined truing speed.

5. A truing apparatus for grinding machines comprising a rotatable grinding wheel, a multi-speed means to rotate said grinding wheel, a truing tool which is arranged to be moved longitudinally and transversely relative to the operative face of said grinding wheel to true said face, means to traverse said tool longitudinally relative to the operative face of the wheel to traverse the truing tool across said face, positioning means to move said truing tool into and out of an operative position relative to said wheel, means to feed the truing tool transversely toward the operative face of the grinding wheel, and a control device operated by said truing tool positioning movement to change the rotative speed of the grinding wheel to a predetermined truing speed.

6. A truing apparatus for grinding machines comprising a rotatable grinding wheel, means including a multi-speed motor to rotate said wheel at either a predetermined grinding or a predetermined truing speed, a truing tool which is arranged to true the operative face of said grinding wheel, means to traverse said truing tool longi-

tudinally relative to the grinding wheel to pass the truing tool across the operative face of the grinding wheel, means to feed the tool transversely to true the operative face of the wheel to the desired extent, means including a rotatable cam to cause the truing tool to move transversely toward and from the periphery of the grinding wheel, means to synchronize the rotation of said cam with the rotation of said grinding wheel so as to generate a predetermined shape on the periphery of said wheel, and means including a control mechanism which serves to change the speed of said motor so as to change the speed of the grinding wheel from a grinding to a predetermined truing speed.

7. A truing apparatus for grinding machines comprising a rotatable grinding wheel, means including a multi-speed motor to rotate said wheel at either a predetermined grinding or truing speed, a truing tool which is arranged to true the operative face of the grinding wheel, means to traverse said truing tool longitudinally relative to the grinding wheel to pass the truing tool across the operative face of the grinding wheel, means to feed the tool transversely to true the operative face of the wheel to the desired extent, means including a rotatable cam to cause the truing tool to move transversely toward and from the periphery of the grinding wheel to true the grinding wheel to a predetermined contour, and means including a control mechanism which serves to change the speed of said motor so as to change the speed of the grinding wheel from a grinding to a predetermined truing speed.

8. A truing apparatus for a grinding machine comprising a rotatable grinding wheel, means including a multi-speed motor to rotate said wheel at either a predetermined grinding or truing speed, a truing tool which is arranged to true the operative face of said grinding wheel, means to traverse said truing tool longitudinally to the grinding wheel to pass the truing tool across the operative face of the grinding wheel, means to feed the truing tool transversely to true the operative face of the wheel to the desired extent, means including a rotatable cam to cause the truing tool to move transversely toward and from the periphery of the grinding wheel, means to rotate said cam in synchronism with the rotation of said grinding wheel so as to generate a predetermined shape on the operative face of the wheel, and a control mechanism operated in timed relation with the truing tool positioning movement toward the operative face of the wheel to automatically change the speed of said motor from a grinding speed to a predetermined truing speed.

9. A truing apparatus for grinding machines comprising a rotatable grinding wheel, means including a multi-speed motor to rotate the wheel at either a predetermined grinding or truing speed, a truing tool which is arranged to true the operative face of said wheel, means to traverse said truing tool longitudinally relative to the grinding wheel to pass the truing tool across the operative face of the wheel, means to move the truing tool toward and from an operating position, means to feed the tool transversely to true the operative face of the wheel to the desired extent, means including a rotatable cam to cause the truing tool to move transversely toward and from the periphery of the grinding wheel, means to rotate said cam in synchronism with the grinding wheel so as to generate a predetermined shape on the periphery of said wheel, and means in-

cluding a speed control mechanism operated in timed relation with the truing tool positioning movement to automatically change the speed of said motor from a grinding speed to a predetermined truing speed.

10. A truing apparatus for grinding machines comprising a rotatable grinding wheel, means including an electric motor to rotate said wheel, a truing tool arranged to true the operative face of the grinding wheel, means to traverse the truing tool longitudinally relative to the grinding wheel to true the operative face thereof, means to move the truing tools to and from an operating position, and means including a variable resistance unit to vary the speed of said motor, and means operated in timed relation with the positioning movement of said truing tool to cut-in said resistance and change the speed of the motor so as to rotate the grinding wheel at a predetermined truing speed.

11. A truing apparatus for a grinding machine comprising a rotatable grinding wheel, means including a multi-speed electric motor to rotate said wheel, a truing tool arranged to true the operative face of said grinding wheel, means to traverse the truing tool longitudinally relative to the grinding wheel to true the operative face thereof, means to move the truing tools to and from an operating position, a variable resistance unit connected with said motor, a limit switch actuated by said positioning movement and arranged to cut-in said resistance to change the speed of said motor to change the speed of the grinding wheel from a grinding speed to a predetermined truing speed.

12. A truing apparatus for a grinding machine comprising a rotatable grinding wheel, means including a multi-speed electric motor to rotate said wheel, a variable resistance unit in series with said motor to vary the speed thereof, a truing tool arranged to true the operative face of the grinding wheel, means to traverse the truing tool longitudinally relative to the operative face of the wheel, means to move the truing tool into and out of an operative position, a relay operatively connected to cut-in said resistance, and means including a limit switch actuated by and in timed relation with the truing tool positioning movement to actuate said relay and cut-in the resistance unit to change the motor speed from a grinding to a predetermined truing speed.

13. A truing apparatus for a grinding machine comprising a rotatable grinding wheel, means to rotate said grinding wheel, a truing tool which is arranged to true the operative face of the grinding wheel, means including a fluid pressure operated piston and cylinder to traverse said tool longitudinally relative to the operative face of said grinding wheel to true the same, a reversing valve to change the direction of movement of said piston, a valve to regulate the speed of movement of said piston, a positioning mechanism to move said truing tool transversely either to or from an operating position, means to feed the truing tool transversely relative to the grinding wheel to true the same to the desired extent, a rotatable cam which is arranged to move the truing tool relatively toward and from the operative face of the grinding wheel during the truing operation, means to synchronize the rotation of said cams and grinding wheel so as to generate a predetermined shape on the periphery of the grinding wheel and a single control member which is arranged to control said reversing valve when

moved in one direction and to control said positioning mechanism when moved in another direction.

14. A truing apparatus for a grinding machine comprising a rotatable grinding wheel, means to rotate said wheel, a truing tool, means including a fluid pressure piston and cylinder which are operatively connected to traverse said truing tool to pass the same across the operative face of the grinding wheel, a reversing valve to change the direction of movement of said tool, means including a nut and screw mechanism to feed said tool transversely relative to the operative face of the grinding wheel to true the same to the desired extent, means including a fluid motor to move the truing tool toward and from an operative position, a valve to control the admission of fluid to said motor, and a single control for said hydraulic mechanism which is arranged so that when moved in one direction is serves to actuate said valve to control the admission of fluid to said cylinder to traverse the truing tool in either direction and when moved in a second direction serves to actuate said valve to control the admission of fluid to said motor to move the truing tool either into or away from an operating position.

15. A truing apparatus for a grinding machine having a rotatable grinding wheel spindle, a plu-

rality of grinding wheels supported thereon for rotation therewith, a plurality of truing tools which are operatively arranged to simultaneously true the operative faces of said wheels, means including a hydraulic piston and cylinder which are operatively connected to simultaneously traverse said truing tools across the operative faces of said grinding wheels, a valve to regulate the speed of said traversing movement, a reversing valve to change the direction of movement of said tools, means to simultaneously feed said tools transversely towards the operative faces of said grinding wheels to true the same to the desired extent, means including an eccentrically mounted shaft which is arranged to simultaneously move the truing tools either to or from an operating position, a fluid pressure motor to rotate said cam-shaft, a second reversing valve arranged to control the admission of fluid to said motor, and a single control for said reversing valve which serves when rotated to actuate said second reversing valve to control the admission of fluid to said motor to control the positioning movement of the truing tools and when moved endwise to actuate said first reversing valve to control the longitudinal movement of said truing tools.
